United States Patent Office

Des. 202,599
Patented Oct. 19, 1965

202,599

DISPOSABLE MEDICAL TRAY

Leonard F. Goyke, Chicago, Ill.
(6301 Lincoln Ave., Morton Grove, Ill.)

Filed Mar. 4, 1965, Ser. No. 84,094

Term of patent 14 years

(Cl. D83—1)

FIG. 3

I claim:

The ornamental design for a disposable medical tray, substantially as shown.
